US00D667607S

(12) United States Design Patent
Schindler

(10) Patent No.: US D667,607 S
(45) Date of Patent:  *Sep. 25, 2012

(54) GARMENT

- (75) Inventor: Heather Thomson Schindler, New York, NY (US)
- (73) Assignee: Times Three Clothier, LLC., New York, NY (US)
- (*) Notice: This patent is subject to a terminal disclaimer.
- () Term: 14 Years
- (21) Appl. No.: 29/350,290
- (22) Filed: Nov. 13, 2009

Related U.S. Application Data

- (60) Division of application No. 29/302,500, filed on Jan. 17, 2008, now Pat. No. Des. 606,285, and a division of application No. 29/350,198, filed on Nov. 12, 2009, which is a continuation of application No. 29/302,500, filed on Jan. 17, 2008, now Pat. No. Des. 606,285.
- (51) LOC (9) Cl. 02-02
- (52) U.S. Cl. D2/702
- (58) Field of Classification Search D2/700-703, D2/731, 732, 828, 840, 718, 737, 847, 714, D2/800, 706, 708, 717, 723, 756, 793, 841; 2/112, 113, 69, 67, 70, 73, 78.1, 78.2, 78.3, 2/104, 105, 109, 110; 450/96, 94, 115, 116, 450/122-124, 127, 132, 154, 10, 15, 30, 450/112, 1, 3, 7, 11, 20, 31, 34, 63, 64, 86, 450/95; 66/176

(57) CLAIM

The ornamental design for a garment, as shown and described herein.

DESCRIPTION

This application claims priority to, and is a divisional application of U.S. Design Application 29/302,500 (now U.S. Design Pat. D302,500), filed on Jan. 17, 2008, the contents of which are hereby incorporated by reference.

This application is related to, and is a continuation application of, U.S. Design Application 29/350,198 (now U.S. Design Pat. D616,627), filed on Nov. 12, 2009, which is a Continuation of U.S. Design Application 29/302,500 (now U.S. Design Pat. D302,500), filed on Jan. 17, 2008, the contents of each application are hereby incorporated by reference.

This application is related to co-pending U.S. Design Application 29/350,288, filed on Nov. 13, 2009, the contents of which are hereby incorporated by reference.

FIG. 1 is a front elevation view of Embodiment 1, of a garment;

FIG. 2 is a rear elevation view thereof;

FIG. 3 is a right elevation view thereof;

FIG. 4 is a left elevation view thereof;

FIG. 5 is a right side elevation view Embodiment 2, of a garment, where the front and rear elevation views are the same as FIGS. 1-2; and,

FIG. 6 is a left elevation view of Embodiment 2, of a garment. The center section and lower section of the claimed design is shaded to illustrate different appearances.

The broken lines shown in the drawings are for environmental structure only and form no part of the claimed design.

1 Claim, 6 Drawing Sheets
